UNITED STATES PATENT OFFICE.

JULIUS SCIANNAMEA, OF NEW YORK, N. Y.

DESK.

1,269,225.

Specification of Letters Patent. Patented June 11, 1918.

Application filed March 7, 1917. Serial No. 153,105.

To all whom it may concern:

Be it known that I, JULIUS SCIANNAMEA, a subject of the King of Italy, and a resident of the city of New York, borough of Manhattan, in the county and State of New York, have invented a new and Improved Desk, of which the following is a full, clear, and exact description.

Among the principal objects which the present invention has in view are: To furnish a desk with concealed means for automatically locking the same; to provide a master releasing device for permitting the desk to be opened under approved conditions; to disguise the structure of the desk; and to provide a piece of furniture of the character mentioned which may be separated into independent parts for transportation.

Drawings.

Figure 1 is a perspective view of a desk constructed and arranged in accordance with the present invention;

Fig. 2 is a perspective view showing a structural unit section thereof;

Fig. 3 is a top plan view of the structure as shown in Fig. 2;

Fig. 4 is a horizontal section, the section being taken as on the line 4—4 in Fig. 6;

Fig. 5 is a horizontal section, the section being taken as on the line 5—5 in Fig. 6;

Fig. 6 is a vertical section, the section being taken as on the line 6—6 in Fig. 5;

Fig. 7 is a cross section of an upper fragment of the desk, the section being similar to Fig. 6, the drawer contained therein being shown in its partially open condition;

Fig. 8 is a longitudinal section on an enlarged scale, showing the top of the desk, the section being taken as on the line 8—8 in Fig. 5;

Fig. 9 is a vertical cross section on an enlarged scale, showing a fragment of the top of the desk, the section being taken as on the line 9—9 in Fig. 8;

Fig. 10 is a detail view in cross section showing a pivot support employed in mounting the drawer stacks.

Description.

As seen in the drawings, the desk consists of two end cabinets or pedestals which are separated in service and serve to support the desk top.

The top referred to has a frame having a table 15, a back rail 16, and side rails 17.

The rails are connected by the braces 18, 19 and 20. The brace 18, as seen best in Fig. 4 of the drawings, extends across the full front edge of the top and serves to support the rails 19 and the drawers 21 and 22, which track thereon. The inner sides of the drawers 22 are protected by partitions 23. The brace 20 is provided as a support for the pivot 24 and the links 25 connected therewith.

The links 25 are operatively engaged with the bolts 26 and serve to retract the same lengthwise when the springs 27 are permitted to extend the links 25 and parts connected therewith to the position shown in Fig. 4 of the drawings.

Normally the links 25 and springs 27 are forced backward by the drawer 21 when the same is in the closed position indicated in Fig. 5 of the drawings. As seen in said figure, when the links 25 are forced backward they operate to spread the bolts 26 for extending the ends thereof through the eyes 28 at the rear of the drawers 22.

It is obvious that when the drawers 22 and 21 are closed in the order named, the first-mentioned drawers cannot be withdrawn from their recesses until the drawer 21 is first opened. This action is assisted by the stop pins 29 which the ends of the bolts 26 engage. The pins 29 prevent the bolts 26 being sprung to permit the movement of the drawers 22.

To lock the drawer 21 in its closed position, is the office of the spring tongue 30, the forward end of which is free to drop behind an abutment 31 at the edge of the brace 18, as seen best in Fig. 9 of the drawings. As shown in said figure, when the drawer 21 is closed, the tongue 30 is held in engagement with the abutment 31. It becomes necessary before said drawer can be drawn from its recess, to disengage the tongue 30. To this end, a spring 32 is disposed on the upper side of the bottom 33 of the recess for the drawer 21. The said spring is provided with a button 34 which extends through a perforation provided in the said bottom 33 and flush therewith. Usually the button 34 is fitted carefully to the perforation provided for it so that the button cannot be readily detected by the fingers when moving under the bottom 33 in search for the lock. The spring 32 serves to maintain the inactive position of the button 34.

When the owner or occupant of the desk presses upward the button 34, he lifts the free end of the tongue 30 from engagement with the abutment 31. While the spring is thus lifted, the drawer 21 may be pulled from its recess and the springs 27 liberated to rock the links 25 and bolts 26 connected therewith so that the ends of the bolts are withdrawn from the eyelets 28.

10 From the above it is obvious that the drawer 21 operates as a master locking device for the drawers 22.

Each of the drawers 22 serves as a locking device for one of the cabinets 35. Each 15 cabinet 35 is provided with a false front 36, which is paneled and provided with drawer knobs 37 in imitation of the drawers with which a desk is usually furnished. Each cabinet is pivotally mounted at the front 20 inner corner thereof on friction-reducing devices such as the bearing balls 38. The balls 38 are mounted in races provided in the plates 39, one of which is in the bottom of the cabinet 35 and the other in the bottom 25 tom 40 of the pedestal wherein the cabinet is mounted.

As seen best in Figs. 1 to 3, inclusive, the cabinets 35 have pigeon-holes 41 and drawers 42 opening from one side of the cabinet, 30 or the outer panels of the pedestals when the cabinets are in closed position. When the cabinets are swung on their pivots outwardly, the openings of the said pigeon-holes and drawers are turned to the outer 35 side and in surrounding relation to the well of the desk or leg space between the pedestals. Normally the cabinets are locked in closed position by pins 43, as shown best in Fig. 6. The pins 43 are mounted at the 40 ends of springs 44 and beneath the cam ends 45. The ends 45 are so shaped and arranged that when the drawers 22 are forced inward, they override said cam ends and force the same downward until the 45 pins 43 extend through perforations 46 in the tops of said cabinets. It is obvious that in this position the cabinets 35 cannot be rotated on their bearings and on the pivot pins 47 thereof until the drawers 22 are 50 withdrawn sufficiently to permit the springs 44 to lift the pins 43 out of engagement with the perforations 46.

As above indicated the desk is constructed so that the top including the table 15, drawers 21 and 22 and supporting structure therefor, and the two pedestals containing the cabinets 35, may be separated and handled as independent elements. The top is secured to the two pedestals by bolts 48 shown best in Fig. 8 of the drawings. The threaded ends of these bolts are passed through perforations 49 in flanges 50 extended inwardly from the outer panel of said pedestals.

65 When the cabinets 35 are closed, the nuts

which engage the bolts 48 below the said flanges are covered and protected from being interfered with. Therefore, an unauthorized person cannot gain access to the interior of the desk by separating the elements thereof.

From the foregoing it will be seen that the master element for releasing the drawers and cabinets of the desk and for giving access to the bolts 48, is to be found in the 75 button 34. As above stated, the button 34 is so shaped that it neatly fits the perforation provided for it in the bottom 33 of the desk top.

The above indicated portion of the desk is 80 normally invisible, and the location of the button would be indicated only to the owner or one having full knowledge of the construction. Further, it will be observed that the location of the button 34 and the perforation for holding the same might be varied to suit the taste of different owners.

When desiring to close the desk, the drawers 42 in the cabinets 35 if previously opened are closed. The cabinets 35 are then swung 90 on their bearings 38 and pins 45 from the position shown at the left of Fig. 1 of the drawings to the position shown at the right of said figure. The drawers 22 are opened to permit the cabinets to swing inward past 95 the pins 43, which are raised normally by the springs 44 out of the path of said cabinets. When the cabinets are in position, the drawers 22 are closed, thereby depressing the free end of the springs 44 and pins 43 connected therewith causing the latter to extend through the perforations 46 in the cabinets 100 to lock the same against rotation.

Prior to closing the drawers 22, it is necessary to partially open the drawer 21 so that 105 the bolts 26 may be retracted from the path of the eyelets 28. When the said drawers 22 have been closed, the drawer 21 is pressed inward against the links 25 to extend the bolts 26, causing the free ends thereof to enter said 110 eyelets. When the drawer 21 has been completely closed, the free end of the spring 30 overrides the spring 32, depressing the same until the face of the button 34 is flush with the lower surface of the bottom 33. In this 115 position the free end of the spring 30 falls behind the abutment 31 and effectively locks the drawer 21, preventing the opening thereof. In this position, unless the person desiring to open the desk is aware of the location 120 of the button 34, or discovers by investigation the said location, it will be found impossible to move the parts to the open position. The knobs 37 on the panels 36 of the cabinets 35, effect a further mystification to 125 one unacquainted with the structure for if the drawers 21 and 22 are operated, the intruder is more apt to endeavor to gain access to the cabinets 35 by pulling on the knobs 37 of the apparent drawer with which they seem 130

to be connected. Pulling on the knobs 37 operates to more effectively close the cabinet, thus defeating the purpose of the unauthorized operator.

5

Claims.

1. A desk comprising a top; drawers slidably mounted in said top adjacent the ends thereof; a plurality of pedestals for said top; a plurality of cabinets pivotally mounted in said pedestals to swing outwardly therefrom; a plurality of locks for holding said cabinets in said pedestals, said locks being actuated by said drawers; a plurality of locks for said drawers; and means normally concealed for releasing said locks, said means actuating a drawer mounted in said top between the first-mentioned drawers.

2. A desk comprising a top; drawers slidably mounted in said top adjacent the ends thereof; a plurality of pedestals for said top; a plurality of cabinets pivotally mounted in said pedestals to swing outwardly therefrom; a plurality of locks for holding said cabinets in said pedestals, said locks being actuated by said drawers; a plurality of locks for said drawers; means normally con-

cealed for releasing said locks, said means embodying a plurality of bolt pins laterally extensible for engaging to restrain the movement of said drawers; and a master drawer adapted for operatively engaging said bolt pins to extend the same laterally for engaging said first-mentioned drawers.

3. A desk comprising a top; drawers slidably mounted in said top adjacent the ends thereof; a plurality of pedestals for said top; a plurality of cabinets pivotally mounted in said pedestals to swing outwardly therefrom; a plurality of locks for holding said cabinets in said pedestals, said locks being actuated by said drawers; a plurality of locks for said drawers; means normally concealed for releasing said locks, said means embodying a plurality of bolt pins laterally extensible for engaging to restrain the movement of said drawers; and a master drawer adapted for operatively engaging said bolt pins to extend the same laterally for engaging said first-mentioned drawers, 50 said master drawer being slidably mounted in service in said top between the first-mentioned drawers.

JULIUS SCIANNAMEA.
